A. McMURTRIE.

BUSHING.

APPLICATION FILED JULY 5, 1918.

1,391,396.

Patented Sept. 20, 1921.

Adolph McMurtie, Inventor

By his Attorney

Alexander C. Provoft

UNITED STATES PATENT OFFICE.

ADNAH McMURTRIE, OF NEW YORK, N. Y.

BUSHING.

1,391,396.

Specification of Letters Patent. Patented Sept. 20, 1921.

Application filed July 5, 1918. Serial No. 243,306.

To all whom it may concern:

Be it known that I, ADNAH McMURTRIE, of New York, N. Y., have invented certain Improvements in Bushings, of which the 5 following description, in connection with the accompanying drawings, is a specification, like characters on the drawings designating like parts.

This invention relates to fittings for electrical conduits, and is of special utility when embodied in the construction of nipples or bushings to be installed at regions where flexible metallic conduits, or metallic sheathed conductors are led through a metallic wall such as the bulkhead of a vessel or the box forming part of a tubular metallic conduit system exposed to moisture in considerable quantities, as for example where a compartment in a vessel is flooded, 20 although it will be understood that I contemplate the use of my improvements in any field for which they are adapted by their nature.

An important object of my invention is to 25 provide a self contained bushing or nipple structure of standard materials or parts, which can be readily installed without the use of special tools or preparation by machining or threading the bulkhead or other 30 partition wall through which the conductor is to be led, permitting also ready removal and replacement of the parts, to permit removal, replacement or adjustment of the conductors.

35 The various features of my invention will be illustrated and described fully in the accompanying drawings and specification and pointed out in the claims.

In the drawings, the figure is a view in 40 vertical section of a bushing in the construction of which my improvements have been embodied, the same being shown in combination with a bulkhead, through which an armored conduit is led, the latter being 45 shown in elevation.

In the embodiment of my invention selected for illustration and description to enable ready and complete understanding of my improvements, the part designated by 50 the reference numeral 1 is a nipple which may be a short section of ordinary piping threaded exteriorly to receive the other members of the bushing, which in the instance illustrated is to be applied to an armored 55 conductor 2 shown with a metallic sheath

3 passing through an aperture 4 in a metal wall 5 which may be considered as part of the water-tight bulkhead of a sailing vessel or steamer.

In accordance with an important object 60 of my invention, I have provided for rendering absolutely watertight the annular space between the sheath 3 and the wall 5, and for this purpose any suitable means may be adopted to carry my invention into effect, 65 and as one convenient form of device for this purpose I have shown on each side of the bulkhead 5 a member 6 combined with gaskets 7 and 8 engaged respectively with the bulkhead 5 and with the sheath 3, the 70 members 6 being threaded internally to enable them to be run upon the nipple 1 so as to force the gasket 7 on each side against the wall 5 surrounding the aperture 4, while the members 6 are also threaded exteriorly 75 to receive inwardly threaded sleeves 9, having flanges 10 to compress the gaskets 8 into water-tight engagement with the periphery of the sheath 3.

From the above description and reference 80 to the drawings it will be seen that no moisture can pass through the aperture 4 from one side of the wall 5 to the other side unless by design the sheath 3 should be used as a fluid conduit, which may be done if 85 occasion should arise, and it is further to be noted that simply by loosening the members 9, without removing them from the members 6, the gaskets 8 can be released from compression, and if formed of elastic 90 material their natural resiliency will result in an enlargement of their central apertures sufficient to permit withdrawal and replacement or re-adjustment of the sheath 3.

It will further be observed that there may 95 be a considerable variation in the size of the metallic sheath 3 or of the hole 4, so that the bushing as a whole may be formed of parts of standard size; also that either gasket 8 and its holding member 9 may be 100 removed without absolutely impairing the water-tight character of the joint on the opposite side of the wall, but under the severe conditions existing in war vessels I prefer to form the device as illustrated. 105

Having illustrated and described my invention thus fully and suitable means to carry the same into effect, I wish it to be understood that I do not limit myself to the specific materials and structural forms 110

selected for illustration and description, nor in general do I limit myself otherwise than as set forth in the claims read in connection with this specification.

5 What I claim as new, and desire to secure by Letters Patent of the United States of America is:—

1. A bushing of the class described, comprising a central nipple threaded exteriorly, 10 a plurality of intermediate nipples threaded interiorly and seated upon said central nipple toward the respective ends thereof, and a plurality of outer nipples screwed upon said intermediate nipples, in combination 15 with a plurality of gaskets interposed between said outer and intermediate nipples in position to be constricted into water-tight engagement with an axially arranged conduit member passing through an aperture 20 in a wall, and gaskets surrounding said central nipple in position to be forced against the opposite sides of said wall, surrounding

said aperture, by engagement of said intermediate nipples with said gaskets.

2. The combination with a wall having an 25 aperture, of a sheath passing through said aperture, a central nipple also in said aperture surrounding said sheath, means to hold said nipple on one side of said wall, an intermediate nipple screwed upon said nipple 30 at the other side of said wall, an outer nipple screwed upon said intermediate nipple, a gasket forming a water-tight joint between said intermediate nipple and said wall, and a gasket forming a water-tight joint between 35 said intermediate and outer nipples and said sheath.

Signed at New York, in the county and State of New York, this 18th day of June, 1918.

ADNAH McMURTRIE.
